Primary Examiner — Steven J Czyz(74) *Attorney, Agent, or Firm* — WPAT, PC(57) **CLAIM**

The ornamental design for a pill box, as shown and described.

DESCRIPTION

FIG. 1 is a perspective view of a pill box showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an operational perspective view thereof, wherein the pill box is shown opened; and,

FIG. 9 is another operational perspective view thereof, wherein the pill box is shown opened.

The broken lines depict portions of the article that form no part of the claimed design.

1 Claim, 9 Drawing Sheets(56)
